eral Motors Corporation, a corporation of Dela-
ware

Application September 20, 1930, Serial No. 483,177

2 Claims. (Cl. 211—153)

This invention relates to refrigerating apparatus and more particularly to the shelf arrangement in such apparatus.

One of the objects of the present invention 5 is to provide improved means for supporting shelves in refrigerator cabinets.

Another object of the invention is to provide an improved shelf for a refrigerator cabinet and to provide means on opposed inner side walls of 10 said cabinet for supporting said shelf, said shelf being readily removable from the cabinet and when removed therefrom the inner walls of said cabinet present substantially flat surfaces which may be readily cleaned.

15 Another object is to provide an improved sliding shelf arrangement in refrigerator cabinets, in which the shelf and its support are readily removable from the cabinet.

Further objects and advantages of the present 20 invention will be apparent from the following description, reference being had to the accompanying drawings, wherein a preferred form of the present invention is clearly shown. In the drawings:

25 Fig. 1 is a view partly in cross section and partly in elevation of a refrigerating apparatus embodying features of the present invention;

Fig. 2 is a view in cross section taken along the line 2—2 of Fig. 1;

30 Fig. 3 is a view similar to Fig. 2 and showing a modified form of shelf arrangement;

Fig. 4 is a fragmentary view of a portion of the apparatus shown in Fig. 3;

35 Fig. 5 is a view of a modified form of shelf arrangement embodying features of the invention;

Fig. 6 is a view in cross section taken along the line 6—6 of Fig. 5;

40 Fig. 7 is a view of a modified form of shelf arrangement embodying features of this invention;

Fig. 8 is a view in cross section taken along the line 8—8 of Fig. 7; and

45 Fig. 9 is a view of a modified form of shelf arrangement embodying features of the invention.

Heretofore it has been the practice to support shelves in refrigerator cabinets on pegs carried by the lining member of the cabinet, or by other devices which permitted rattling of the shelves 50 when food articles were placed upon or removed from said shelves, or by the motion of the machine in the cabinet. In an arrangement of this type the shelves were loosely supported by the lining member of the cabinet and in many instances it was necessary to provide additional clamps for securing the shelves to the cabinet during transportation thereof.

55 This invention is concerned with an improved 60 shelf arrangement in refrigerator cabinets, in

which the shelves are rigidly secured to the inner walls of the cabinet but readily removed therefrom and when removed therefrom the inner walls of said cabinet present a substantially smooth and flat surface which may be easily cleaned. 5

Referring to the drawings and particularly Figs. 1 and 2, the numeral 20 designates in general a refrigerator cabinet embodying features of the present invention. The cabinet 20 comprises in general side walls 22, front wall 23 and rear wall 24. The walls 22, 23 and 24 are provided with insulation 27 interposed between an inner metal lining 30 and an outer casing 32. The front wall 23 is provided with an opening 10 35 closed by a door 36. An expansible shelf 40 is provided for supporting articles to be refrigerated. 15

The shelf 40 is of the open work type having an outer wire member 42 providing sides 43, 44, 20 45 and 46. A plurality of wire strands 47 extend across the sides 44 and 46 and are secured to said sides of the wire member 42 preferably by solder. The side 43 of the shelf 40 is formed to provide a plurality of spaced apart projections 50. The side 45 of the shelf 40 is provided with a plurality of threaded lugs or projections 52. Preferably the projections 52 include adjustable members 54 provided with arcuate portions 55. The projections 50 and 52 are adapted to 25 30 35 cooperate with the inner metal lining member 30 to thus support the shelf member 40 by said lining member in a manner about to be described.

In order to provide means for supporting the shelf member 40 by the lining member 30 there is provided in opposed side walls of the lining a plurality of spaced apart slight indentations or 40 dimples 57 and 59. The projections 50 and 52 are adapted to be received in the dimples 57 and 59 respectively. The projections and dimples preferably have the shape of spherical segments. Since the shelf is expansible due to the adjustable member 54, the projections 50 can first be inserted into the dimples 57 and the projections 52 aligned with the dimples 59 and then the adjustable members 54 may be turned until the arcuate portions 55 tightly engage the dimples 59 of the lining member 30. By this arrangement the shelves may be readily removed from or inserted into the cabinet. Also, this arrangement 45 50 55 prevents rattling of the shelves since the shelves are rigidly secured to the lining member.

In the modification shown in Figs. 5 and 6 a lining member 70 for a refrigerator cabinet is adapted to support a shelf member 72 by means 55 of an expansible shelf supporting member 74. In this particular embodiment the shelf supporting member is provided with a plurality of lugs or projections 76 provided with arcuate portions 77 substantially of the form of spherical segments 60

and a plurality of adjustable projections 79 provided with arcuate portions 79a also of the form of spherical segments. The shelf supporting member 74 is provided with curled edges 80 and 81 which are adapted to provide slide-ways for the shelf 72. The shelf supporting member 74 is also provided with longitudinally extending tie members 84 preferably formed integrally with the curled edges 80 and 81 for maintaining the curled edges 80 and 81 in spaced relation. The tie members 84 are provided with beaded portions for strengthening said tie members. Preferably the projections 77 and the adjustable projections 79 are welded to the shelf supporting member. In order to support the shelf by the lining member 79 there is provided a plurality of slight indentations or dimples 90 and 92. The dimples 90 are adapted to receive the projections 77 while the dimples 92 are adapted to receive the adjustable projections 79. These dimples preferably take the form of hollow spherical segments. Since the shelf 72 is slidably supported by the shelf supporting member the wire strands 95 are provided with upwardly directed portions 97 which serve to prevent dishes or the like from sliding off the shelf when said shelf is being pulled toward the front of the cabinet. Also the upturned portions 97 serve as bumpers to prevent the heavy wire portion 98 of said shelf from engaging the rear wall of the lining member. By this particular arrangement the shelf member 72 may be slid along the slideways 80 and 81 until the entire shelf member is removed from the cabinet through the front door opening, or said shelf may be removed sufficiently from the cabinet to give ready access to articles placed on the rear portion of said shelf member. Preferably the shelf member and the self supporting members including projections 77 and 79 are coated with a non-corroding plating.

If desired, the shelf 72 may be provided with means which limits the outward movement thereof to thus prevent the rear portion of said shelf from tipping downwardly by the unexpected removal of the rear portion of said shelf from its support. This means comprises a wire member 100 carried by the wire strands 95 and a movable stop 101 which may be secured to the curled edge 80 in any suitable manner and at any desired place along said curled edge. The stop 101 includes a movable finger 103 pivotally mounted at 105. Since the pivot point 105 of finger 103 is off-center and the side 108 thereof is the heaviest, the finger will remain in the position shown in the drawings to serve as a stop until said finger is manually actuated to a vertical position. When the finger 103 is in a vertical position the wire member 100 will clear the stop to thus permit the shelf to be entirely removed from the cabinet.

Referring to Figs. 7 and 8 there is shown a modified form of shelf construction and shelf arrangement in a refrigerator cabinet. In this particular embodiment a lining member 110 is adapted to support an expandable shelf member 112. The shelf member 112 is similar to the shelf member 40 with the exception that a plurality of lugs or projections 115 are secured to the outer wire member 119 instead of said outer wire member being formed to provide projections as shown in Fig. 1 at 50. Thus the projections 115 and a plurality of adjustable projections 120 are adapted to cooperate with a plurality of slight indentations or dimples 121 provided in the lining member

110 for supporting the shelf member 112 by the lining member 110.

In the modification shown in Fig. 9 the shelf members 123 may be supported by slight indentations or dimples provided in opposite walls of the cabinet 125 in a similar manner as shown in Figs. 1 to 5, 6, 7 and 8. However, the opposite walls in this modification may be one or more partition walls 130 which may be provided with a plurality of dimples for receiving the projecting lugs carried by said shelf. In this embodiment the partition wall 130 is used to form a housing for a cooling element (not shown). The dimples in the partition wall may be the same as the dimples in the lining members 30, 70 and 110.

Referring now to Figs. 3 and 4 there is shown a modified form of shelf arrangement for a refrigerator cabinet. As shown the lining member 135 is adapted to support a shelf member 137. In this particular embodiment the lining member 135 is provided with a plurality of projections 140 and 140a substantially of the form of spherical segments and the shelf member is provided with one or more dimples 142 and one or more adjustable dimples 143, all of which have a portion 25 of their surface of spherical contour. In this particular arrangement the wire member 150 of the shelf 137 is looped to provide a threaded eye portion 152 adapted to receive a set screw 145. The set screw 145 is adapted to carry the dimple portion 143 with said dimple portion rotatably mounted on the one end thereof. In order to insert or remove the shelf from the cabinet all that is necessary is to place the dimple portion 142 over the projection 140 and then turn the 30 adjustable screw threaded member for causing the dimple 143 to engage or disengage the projection 140a.

While the form of embodiment of the invention as herein disclosed, constitutes a preferred 40 form, it is to be understood that other forms might be adopted, all coming within the scope of the claims which follow.

What is claimed is as follows:

1. A refrigerator cabinet having an inner sheet metal lining member, said lining member having deformed portions on opposite wall sections, a shelf structure including a rectangular member having a supporting surface and a bounding member extending around its perimeter, said bounding member having deformed portions on one side provided with means for engaging some of the deformed portions of the lining member to support the shelf structure at one side and projections on the opposite side of the bounding frame provided with adjustable means for engaging other deformed portions of the lining member to support the shelf on the opposite side.

2. A refrigerator cabinet having an inner sheet metal lining member, said lining member having deformed portions upon opposite wall sections, a shelf structure including a rectangular member having a supporting surface and a bounding member extending along its perimeter, said bounding member having arms extending therefrom on one side provided with means for engaging some of the deformed portions of the lining member to support the shelf structure at one side, and projections on the opposite side of the bounding member provided with adjustable means for engaging other deformed portions of the lining member to support the shelf on the opposite side.
